United States Patent Office

Des. 186,275
Patented Oct. 6, 1959

186,275

COMBINED GATE POST AND GATE

Louis Blum, Pittsburgh, Pa.

Application October 22, 1956, Serial No. 43,456

Term of patent 14 years

(Cl. D28—1)

FIG. 1.

FIG. 2.

FIG. 3.

Fig. 1 is a front elevational view of a combined gate post and gate, showing my new design.

Fig. 2 is a view along the line II—II of Fig. 1.

Fig. 3 is a view along the line III—III of Fig. 1.

The dominant features of my design reside in the portions shown in full lines.

I claim:

The ornamental design for a combined gate post and gate, as shown and described.
